ANNEALING BOX

Kenneth J. Deahl, Pittsburgh, Pa., assignor, by
mesne assignments, to Pittsburgh Annealing
Box Company, Pittsburgh, Pa., a corporation
of Pennsylvania

Application April 28, 1937, Serial No. 139,577

7 Claims. (Cl. 263—49)

My invention relates to annealing boxes and more particularly to those formed of sheet metal.

One object of my invention is to provide an annealing box of such form which for a given weight or gauge of metal will have greater strength and resistance to deformation and, therefore, will be serviceable for a greater number of "heats" than will boxes of other forms.

Another object of my invention is to provide an annealing box of corrugated metal sheets wherein there is an improved arrangement of bracing and stiffening members so arranged as to reinforce and prevent deformation of the corrugations, with consequent greater resistance to any tendency of the corrugations to spread and flatten under temperature changes and other stresses, particularly in the zones where the application of furnace heat is most intense.

Still another object of my invention is to provide a box wherein the zone adjacent to the bottom edge that is subjected to the greatest intensity of furnace heat, is so formed as to have greater flexibility under temperature changes than is required or desired for other portions of the box.

Some of the forms which my invention may take are shown in the accompanying drawings wherein Figure 1 is a fragmentary side view of the box, partly in section; Fig. 2 is an end view thereof; Fig. 3 is an enlarged view taken on the line III—III of Fig. 1; Fig. 4 is a view taken on the line IV—IV of Fig. 3; Fig. 5 is a view taken on the line V—V of Fig. 3; Fig. 6 is an elevational view of the structure of Fig. 5, partly in section; Fig. 7 is a sectional plan view of the box, taken on line VII—VII of Fig. 1; Fig. 8 is an enlarged view taken on the line VIII—VIII of Fig. 7; Fig. 9 is a view taken on the line IX—IX of Fig. 8; Fig. 10 shows a modification of the structure of Fig. 9, and Fig. 11 shows still another modification thereof.

Referring first to Figs. 1 to 9, the box is constructed of metal sheets or plates which are welded together at their abutting edges to produce a unitary box structure having side walls 10, end walls 11, and a top wall 12.

The walls of the box are so shaped as to have oppositely-projecting corrugations or channels 13 and 14 formed therein that are substantially co-extensive with the walls of the box, the channels in the side walls matching the channels in the top wall and being in effect continuous therewith. These channels, of course, serve to stiffen the structure and enable it to be made of lighter gauge material than would otherwise be possible.

The vertical channels in the side walls extend to the bottom edge of the box and serve to give greater area of support to the box.

The temperature changes to which the box is subjected are, of course, very great, and the tendency toward distortion or deformation is very great, owing to the fact that parts of the box become heated or cooled much more quickly than other parts thereof. For example, the portion of the box disposed in the sand seal does not follow changes in temperature as rapidly as other parts of the box, consequently the box near its bottom edge is subject to extreme differences in temperatures.

The corrugations 13, near the bottom edge of the box, are deformed or flattened somewhat, as shown more clearly at 15 in Figs. 1 and 4, to produce flutes or partial folds in the walls of the corrugations, in order to provide for greater yieldability or flexibility at that portion of the box, under temperature changes, since in many types of annealing furnaces, the heat of the burners is applied to the exterior wall of the box near its lower edge, with consequent greater expansion and contraction of the metal. It will be understood that the extreme lower edge of the box which rests in the sand will become heated much more slowly than that portion of the box immediately above the sand seal. On the other hand, if the box is permitted to cool while still in the sand seal, the portion above the sand will cool much more rapidly than the lower edge of the box. The greater flexibility provided in the lower portions of the corrugations consequently permits of greater relative expansion and contraction of the box walls at such points without cracking or deforming the metal, such as so frequently happens in the case of either ordinary corrugated wall or flat wall boxes. The sand trough 16 and the sand seal formed therein may be of any well-known arrangement; but in this case can be made narrower, owing to the compressed or flattened corrugations, thus reducing the amount of sand required to effect proper seal and thereby effecting a more rapid response to temperature changes between the portion of the box in the sand and that portion just above the sand. In addition, by the use of the narrowed sand trough and the flattened wall corrugations, a furnace of a given size will accommodate a box of a somewhat larger "charge" capacity.

The side and end walls of the box have their corrugations strengthened and stiffened by box-

like arrangements of reinforcing and stiffening members, as hereinafter described.

In the case of the outwardly-projecting channel-like corrugations 13, I stiffen the same by the use of elements comprising a stem portion 17 and a channel-like portion 18, which are suitably welded together. The stiffening members 17-18 are of a length substantially equal to the width of such corrugation or channel 13, and the outer edge of the element 17 is welded to the web of such channel. The ends of the elements 17 and 18 are welded to what are in effect the side walls of the corrugations 13, as indicated at 19. The element 17 is welded to the channel-like element 18 along a line preferably mid-way between the flanges of the channel, before the members 17 and 18 are welded to the corrugations. The members 17 and 18 in effect constitute a shape that is of generally T-form in cross section.

On the outer side of the box, I provide continuous channels 20 disposed with their flanges abutting the outer surfaces of the corrugations 13 and welded thereto. Reinforcing plates 21 equal in length to the width of the corrugations 14 are welded to the channels 20 before the channel is secured to the box, the inner edges and ends of the plates 21 being welded to the web and side walls of the corrugations 14.

Since the filler plates 21 are of short length and do not extend across the outermost surfaces of the channels 18, there may be flow of heated gases upwardly along the corrugations 14, through paths behind the lowermost flange of the channel 20, around the ends of the plates 21 and upwardly behind the upper flange of the channel, as indicated by the arrows in Fig. 1, thus permitting all portions of the outer side of the box to be exposed to flow of heated gases although reinforced by the channel and the plates 21.

The channels 20 not only serve to distribute distortions of the side walls to the various vertical corrugations, thus preventing excessive deformation and flexing of only certain corrugations, which would result in early cracking of the metal, but by reason of their form and arrangement they tend to restore the box to its original contour after each heating and cooling cycle. This latter function occurs by reason of the fact that the inner edges of the flanges of channels 20 are in spaced relation to the webs of the inwardly projecting corrugations 14, as shown more clearly in Fig. 7. As above stated, the heated gases flow upwardly through the corrugations, past the inner edges of the channels 20, which results in comparatively rapid heating of those portions of the channels 20 which are opposite to the corrugations 14, because such channel portions are out of contact with the colder box surface and the heat is not readily conducted therefrom to the box wall nor to the metal contents within the box. The colder portions of the structure resist the tendency of these hotter portions of the channel to expand under the initial heat, with the result that these hotter portions are placed under high compression.

After an annealing operation and during the cooling cycle, the said spaced portions of the channels 20 will cool more rapidly than those portions of the channels which are opposite to and in contact with the corrugations 13. Consequently, those said spaced portions of the channels will tend to contract rapidly and exert such tensional forces as will be effective to return any heat-distorted portions of the box back to approximately its original form. The webs 21 serve

to stiffen and hold the spaced portions of the channels 20 from excessive distortion under temperature changes. In practical use of these boxes, it has been shown that instead of the whole side of a box bulging out in the form of a curve, the bulging is confined to small amounts inwardly and outwardly at the various corrugations.

Referring now to Fig. 10, I show a structure wherein the stiffening members for the outwardly-projecting corrugations 13 may be the same as above described, but in this instance I provide an outer strengthening channel 24 whose flanges are of sufficient depth or width to engage the exposed surfaces of the corrugations 14, the intermediate portions of the flanges being cut 15 away opposite the corrugations 13. The flanges of the channels 24 are welded to the adjacent surfaces of the corrugations 13 and 14, and no stiffening plates such as 21 are required. Portions of the flanges are further cut away as indicated at 26, in order to permit vertical flow of hot gas along the corrugations 14.

In Fig. 11 I show a structure wherein the outwardly-projecting corrugations are braced and strengthened by the elements 28 and 29 which correspond to and are mounted in the same manner as are the elements 17 and 18 of Fig. 8. In this structure, the outwardly-projecting corrugations are provided with reinforcing plates 30 and channels 31 that are substantially duplicates of the members 17 and 18 or the members 28 and 29.

The members 28 and 29 are preferably in horizontal alignment with the members 30 and 31, and since each of these members is welded at its ends to the adjacent corrugation walls, they in effect form a stiffening channel extending throughout the periphery of the box.

I claim as my invention:

1. The combination with an annealing box having corrugations formed in its walls, of stiffening members consisting of channels secured at their ends to the sides of the corrugations, and reinforcing plates disposed within said channels and secured to the channels and to the corrugations.

2. The combination with an annealing box having corrugations formed in its walls, of stiffening members comprising channel-like elements, and reinforcing elements secured to the inner surfaces of the channels and to the walls of the corrugations, the reinforcing elements extending in directions parallel to the flanges of the channel elements.

3. The combination with an annealing box having inwardly and outwardly-projecting corrugations formed in the walls thereof, of stiffening members for each of said corrugations, comprising channel-like elements disposed within the corrugations and secured thereto, the stiffening members positioned within the inwardly-projecting corrugations being in longitudinal alignment with the stiffening members located within the outwardly-projecting corrugations.

4. The combination with an annealing box having vertically-extending corrugations formed in its walls, of a stiffening element of channel form disposed transversely of and secured to the corrugations, and reinforcing plates secured to the channel and to the box at points between the said corrugations.

5. The combination with an annealing box having corrugations of channel-like shape formed in the walls thereof, of channels extending transversely of said corrugations and having portions

of their edges welded to adjacent portions of the corrugations and intermediate portions of said edges disposed in outwardly spaced relation to relatively depressed portions of the corrugations.

5. The combination with an annealing box having corrugated walls, of channels extending transversely of said corrugations and having portions of their edges welded to the outermost areas of the corrugations and other portions spaced outwardly from the depressed areas of the corrugations, and reinforcing plates having their inner edges secured to the said depressed areas and their outer edges secured to the webs of the channels.

10

7. The combination with an annealing box having corrugated walls, of channels extending transversely of said corrugations and having portions of their edges welded to the outermost areas of the corrugations and other portions spaced outwardly from the depressed areas of the corrugations, and reinforcing plates having their inner edges secured to the said depressed areas and their outer edges secured to the webs of the channels, the said reinforcing plates extending parallel to 10 the channels and disposed approximately midway between the flanges of the channels.
